John T. King,

UNITED STATES PATENT OFFICE.

JOHN T. KING, OF MADISON, WISCONSIN, ASSIGNOR TO WALKER & CO., OF SAME PLACE.

CYLINDER PRINTING-MACHINE.

SPECIFICATION forming part of Letters Patent No. 377,432, dated February 7, 1888.

Application filed April 5, 1887. Serial No. 233,781. (No model.)

To all whom it may concern:

Be it known that I, JOHN T. KING, of the city of Madison, county of Dane, and State of Wisconsin, have invented certain Improvements in Cylinder Printing-Machines, of which the following is a specification, reference being had to the accompanying drawings.

My improvements relate to printing-presses in which there is a type-bed that is alternately raised and lowered—that is to say, raised to make the impression on the paper carried over it by a reciprocating roller-cylinder and then lowered while the cylinder returns.

The object of my improvements is to provide means for raising and lowering the type-bed in a straight line at right angles to the impression-surface of the bed and for holding it firmly while taking the impression.

My invention consists in the combination of appliances for these purposes, hereinafter described, and succinctly stated in my appended claims.

My improvements are illustrated as applied to the kind of press known as the "Prouty press," shown in United States Patents Nos. 206,826 and 249,989, which it is not necessary to describe in detail.

I have found by experience that when the type-bed is raised and lowered by an oscillating movement, as is the case in the said patents, at times, when forms are moved well forward, accidents are liable to occur, resulting in the grippers striking across the head-rule and smashing both grippers and head-rule. Such accidents are entirely obviated through my improvements, by which the type-bed is raised and lowered vertically or in a straight line and firmly held by my appliances while the impression is being taken. I provide bars or tracks, which are fast to the type-bed, so that the type-cylinder not only treads upon the rail of the press-frame, but also upon these tracks, which prevents any jarring of the cylinder between forms or pages. As the bed is tripped or lowered, the tracks go with it, and they serve for the travelers on the form-rollers to run upon.

In the drawings, Figure 1 is a plan view of

a press adapted to the application of my invention. Fig. 2 is a longitudinal section on the line 2 2 of Fig. 1. Fig. 3 is a longitudinal section on the line 3 3 of Fig. 1, viewed from the opposite direction from Fig. 2. Fig. 4 is a transverse section on the line 4 4 of Fig. 2, and Fig. 5 is a detail section of part of the main frame and track.

Referring to the letters upon the drawings, X indicates the main frame; Y, one of the main driving-shafts, which makes a revolution at each impression; and Z, a part of the rocking support of the type-bed.

The operative parts, not here quite fully illustrated and not described, are essentially such as shown in my United States Letters Patent No. 361,423, issued April 19, 1887, which form no part of my present invention.

It will be understood that the type-bed rests upon suitable rocking supports whose movement, by connection with the rotating parts at the proper time, slightly raises and lowers the bed, as is done on a similar principle in many presses of this general class.

Referring now more particularly to the parts which, organized together, constitute my improvement, A' indicates sliding bars underneath the type-bed, provided with sockets a.

B' indicates round-headed screw-bolts passing through the oscillating bar Z, in which they are adjustable for leveling the type-bed, and their heads enter the sockets a.

E' is an arm secured to one of the bars Z, and provided with a screw, e. When the bar Z is oscillated, so as to raise the type-bed into position for taking the impression, the screw e will bear against the end of the bed and hold the bar firmly. This screw is adjustable so as to serve that purpose.

C' indicates the tracks upon either side of the type-bed. The oscillation of the bar Z will cause the sliding bars A' to slide on the under side of the type-bed, D' without moving it, which will cause the type-bed and the tracks C' to be raised and lowered vertically the proper distances.

What I claim to be new, and desire to secure by Letters Patent of the United States, is—

1. The combination, with the oscillating bars Z and bolts B', of the sliding bars A', the type-bed, and tracks C', substantially as set forth.
- 5 2. The combination, with the oscillating bars Z and bolts B', of the sliding bars A', the type-bed, tracks C', the arm E, and screw e, substantially as set forth.

In testimony whereof I have hereunto subscribed my name.

JOHN T. KING.
